UNITED STATES PATENT OFFICE

2,641,035

WALL CONSTRUCTION AND CLIP THEREFOR

Nels Nelsson, Chicago, Ill., assignor to United States Gypsum Company, Chicago, Ill., a corporation of Illinois

Application March 4, 1950, Serial No. 147,733

4 Claims. (Cl. 24—73)

1

This invention relates to wall constructions and more particularly to that type known as furred walls. It relates also to an improved form of clip used to secure the furred wall members to the furring strips or wall supports.

Furred walls are employed ordinarily to afford a straight even exposed wall surface or to provide an air space between the base wall and the furred wall for purposes of sound and heat insulation, or to present matching surfaces at partitions. A number of systems have been developed to obtain a furred wall, many of which systems employ wooden strips secured to the base wall to which strips the finishing or furred wall elements are secured. Other systems employ metal furring strips or supporting members, clips being used to secure the furred wall elements to the furring members. It is to the latter type of furred wall construction that the present invention relates.

It is an object of the present invention to provide a furred wall construction which may be readily and easily erected and which will afford a secure connection between the furred wall elements and the furring strips.

It is a further object of the invention to provide a furred wall construction which is particularly adapted for use in connection with wall boards of the lath type, such as gypsum or plaster lath, fiber board, and other similar wall elements which are manufactured in sheet or panel form.

Another object of the invention is to provide a novel form of clip whereby the wall boards may be readily secured to the furring members with the wall boards in coplanar edge to edge relationship.

Other advantages will appear to those skilled in this art as the description proceeds.

The invention will be best understood by reference to the accompanying drawings, forming a part of this application, in which the same numerals refer to corresponding parts. In the drawings

Figure 1 is a cross section through a wall construction embodying the preferred form of the invention, the section being taken through the adjoining edges of two wall boards with the improved clip shown in plan view;

Fig. 2 is a section taken on line 2—2 of Figure 1;

Fig. 3 is a perspective view disclosing the improved clip applied to a furring strip and wall boards, the clip being shown in full lines, the remainder of the construction being shown in dotted lines;

2

Fig. 4 is a sectional perspective view of the improved wall construction as viewed from the front or exposed surface of the furred wall;

Fig. 5 is an elevation of the clip as viewed in the direction of arrow X in Fig. 3; and

Fig. 6 is an elevation of the clip as viewed in the direction of arrow Y in Fig. 4.

Referring now to the drawings in which one practical embodiment of the invention is illustrated, the base wall is shown at 10. This may be of concrete, brick, wood, or any other construction. To the inner side of the base wall 10 are secured in spaced parallel relationship furring strips 11, preferably in the form of steel channels such as are frequently used in this type of wall construction. The furring strips may, of course, be formed of any metal or of wood of sufficient rigidity, the same being secured to the base wall 10 by suitable securing brackets 12 and tie wires 13. The details of the latter construction form no part of the present invention, as any suitable means may be employed for securing the furring strips to the base wall.

Resting against the front or exposed sides of the furring strips are the wall boards 14 and 14' which, in the drawings, are shown as plaster or gypsum boards which are formed of a gypsum core disposed between paper liners. Of course any type of wall boards in sheet or panel form, such as those made of wood fiber, asbestos, and the like, may be used.

The wall boards 14 and 14' are arranged in coplanar edge to edge relationship upon the furring strips and are secured thereto by clips 15 which may be arranged at suitable intervals along the edges of said boards at the points of their registration with the furring strips. The clips 15 are preferably made of a relatively stout resilient round steel wire, although the wire may, of course, vary in cross section and may be formed of any suitable material having sufficient strength and resilience. Each clip is formed of an intermediate or shank portion 16 which is adapted, when the clip is in use, to pass through the joint between the adjacent edges of adjoining wall boards, as best seen in Figs. 1 and 4. The length of the shank 16 corresponds substantially with the thickness of the wall boards with which it is used.

At the rearward end of said shank is formed an attaching hook which comprises an extension 17 which extends angularly or obliquely from said shank and which extension, when the clip is in use, is adapted to rest upon the upper side of the furring strip. Extending downwardly from the

rear end of the extension 17 and at right angles thereto is a hook portion 18 which is adapted to engage behind the furring strip so as to anchor the clip thereto. An offset detent 19 at the lower end of the portion 18 is adapted to engage under the furring strip so as to hold the hook in engagement therewith. The angle A formed between the shank 16 and the extension 17, as seen in Fig. 1, is preferably about 45°, although this may vary, it having been found that any angle between 30° and 70° is suitable. The angular disposition of the extension 17 with respect to the shank 16 will vary somewhat with the width of the furring strip with which it is designed to be used.

At the front end of the shank 16 is a U-shaped loop, the plane of the loop being perpendicular to the shank. Said loop is formed of two substantially parallel legs, 20 and 21, connected by the bight 22. The leg 20 is disposed in the same plane as the shank 16 and the extension 17. The leg 21 is longer than the leg 20 so that when the clip is in use the loop thereof will rest flatly against the front face of the edge portion of one of the adjoining wall boards while the free end of the leg 21 will span the joint between the boards and engage against the front face of the edge portion of the other board, as best seen in Figs. 1 and 4. The terminal portion 23 of the leg 21 is bent outwardly slightly so as to facilitate engagement of the board edge therewith.

It will be observed that the extension 17 and the leg 20 of the loop extend from the same side of the shank 16 so that the bight 22 of the loop is directly opposite the furring-strip-engaging portion 18. That is to say, when the clip is in position, a line drawn through the portion 18 and the bight 22 of the loop will be substantially parallel with the shank 16. With this arrangement a clamping action is developed between the clip and the furring strip and wall board 14, which serves to securely hold these parts in assembled relation.

The angular disposition of the portion 17 of the clip with respect to the shank 16, that is to say the angle A, is important in order to insure a clamp-like grip of the clip with the furring member and wall board. While this angle can vary within a wide range, it has been found, as before indicated, that about 45° is satisfactory where the clip is used with a $\frac{3}{4}$ " furring channel and wall board $\frac{1}{2}$ " thick. With the channel and wall board of the dimensions indicated, and with the extension portion 17 of the clip disposed at a 45° angle, as indicated, the bight 22 of the loop 15 is directly opposite the portion 18 of the clip which engages behind the furring channel. However, this is not critical for the loop can be relatively longer or shorter than shown which, of course, will vary the relative position of the bight thereof with respect to the portion 18 of the hook of the clip. With a wider furring member and the same loop, a line drawn from the bight through the portion 18 would not be parallel with the shank 16 of the clip. The dimensions of the clip must be such as to enable the loop portion thereof to snugly engage the wall board and the hook portion of the clip to snugly engage over and behind the furring member to produce the clamping action which will hold these parts in secure relation with each other. Channel furring strips and gypsum wall board are manufactured within fairly close dimensional tolerances and the clip may, therefore, be designed with the dimensions of these parts in mind. Where different

widths of furring members and different thicknesses of wall board are employed, it will, of course, be necessary to vary the dimensions and details of the clip to accommodate the same to such furring members and wall boards, in order to obtain the best results. At the present time, however, $\frac{3}{4}$ " channels and gypsum wall board $\frac{1}{2}$ " thick are in general use so that clips designed with these dimensions in mind will function properly with the majority of structures. The clips are of such construction as to lend themselves to ready manufacture in various sizes and proportions and with a changed angle A in order to accommodate the clips to other sizes of furring members and wall boards.

In the structure illustrated in the drawings the furring strips are horizontally disposed and the wall boards vertically. It is, of course, understood that the clips are also usable where the furring strips are disposed vertically and the wall boards horizontally.

In use the wall boards are usually supplied with a finishing coat of plaster, which coat, of course, covers the exposed portions of the clips. Inasmuch as a finishing plaster coat is normally employed with the construction in question it is preferable to employ wall boards having an exposed surface of paper or of such character that a plaster coat will readily adhere thereto.

With clips of the construction described, wall boards may be readily and quickly attached to furring strips by workmen of very ordinary skill. By the use of such clips the boards and the furring strips will be effectively clamped together and the completed furred wall will be rigid and firm. Moreover the clips are so constructed as to permit of ready and economical manufacture.

While I have illustrated and described the preferred form of my invention, I do not wish to be limited thereto, but desire to avail myself of such modifications as come within the spirit and scope of the appended claims.

I claim:

1. A clip for securing wall boards arranged in coplanar edge-to-edge relationship to one edge of a furring member, said clip comprising an intermediate portion adapted to be disposed in the joint between two adjoining boards, a board-engaging portion at one end of said intermediate portion in the form of a loop of substantially U shape with the bight portion of said loop adapted to rest flatly against the front surface of one of said boards and with one of the legs of said loop longer than the other and adapted to rest against the front surface of the other board, and means at the opposite end of said intermediate portion adapted to engage the inner edge of said furring member, said intermediate portion being bent adjacent the outer edge of said furring member in such a direction that said means lie substantially directly inwardly of a part of the board engaging portion overlying one of said boards, whereby said clip includes a U-shaped construction capable of clamping said one board to said furring member independent of another abutting board.

2. A clip for securing wall boards arranged in coplanar edge-to-edge relationship to the outer edge of a furring member, said clip comprising a head for spanning the joint between adjacent boards and to overlie the edge portions of two boards adjacent said joint, a shank portion for extending inwardly through said joint and to the inner edge of said furring member, and a hook portion for engaging the inner edge of said

furring member, said shank portion being bent adjacent the outer edge of said furring member in such a direction that said hook portion lies substantially directly inwardly of a portion of said head overlying one wall board, whereby said hook portion, said shank portion, and said portion of said head may clamp said one wall board to said furring member independent of another abutting wall board.

3. A clip for securing wall boards arranged in coplanar edge-to-edge relationship to the outer edge of a furring member, said clip comprising a head for spanning the joint between adjacent boards and to overlie the edge portions of two boards adjacent said joint, a shank portion for extending inwardly through said joint and to the inner edge of said furring member, and a hook portion for engaging the inner edge of said furring member, said shank portion being bent adjacent the outer edge of said furring member in such a direction that said hook portion lies substantially directly inwardly of a portion of said head overlying one wall board, whereby said clip includes a U-shaped construction capable of clamping said one wall board to said furring member, independent of another abutting wall board.

4. A wire clip for securing wall boards arranged in coplanar edge-to-edge relationship to the outer edge of a furring member, said clip comprising an intermediate portion for extending directly inwardly through the joint between said boards, a head portion at the outer end of

said intermediate portion for spanning said joint and to overlie the edge portions of said boards adjacent said joint, an angled portion extending generally inwardly from the inner end of said intermediate portion at an acute angle with respect to the plane of said joint, said intermediate portion and said angled portion defining a plane substantially perpendicular to the plane of said joint, and a hook portion for engaging the inner edge of said furring member, said hook portion extending from the inner end of said angled portion in a direction perpendicular to a parallel of said intermediate portion and at a substantial angle to the plane defined by said intermediate portion and said angled portion, said angled portion, said intermediate portion, and a part of said head portion adapted to overlie one of said boards forming a generally U-shaped construction whereby a part of said hook portion is arranged directly inwardly of a part of said head portion and whereby a single board may be clamped to said furring strip independent of another abutting board.
